UNITED STATES PATENT OFFICE.

HENRY H. ROGERS, OF BROOKLYN, NEW YORK, ASSIGNOR TO "CHARLES PRATT MANUFACTURING COMPANY," OF NEW YORK CITY.

IMPROVEMENT IN NOZZLES FOR LIQUID-PACKAGES.

Specification forming part of Letters Patent No. 118,154, dated August 15, 1871.

To all whom it may concern:

Be it known that I, HENRY H. ROGERS, of Brooklyn, in the county of Kings and State of New York, have invented an Improved Nozzle for Liquid-Packages; and I do hereby declare the following to be a full, clear, and exact description of the same, reference being had to the accompanying drawing forming part of this specification, in which—

Figure 1 is a side elevation, partly broken away to show the interior arrangement of the discharge-spout; and Fig. 2 is a vertical section of the nozzle, showing the top cut away and the spout arranged for the discharge of the liquid.

Similar letters of reference in the accompanying drawing indicate corresponding parts.

My invention has for its object to provide an improved nozzle or top for liquid-packages; and to this end it consists in placing a spout within a recessed nozzle, which spout, when the seal of the nozzle is broken, forms a discharge-tube for the liquid. The nozzle is made complete for the market, with the top sealed and containing the spout. When applied to a can, therefore, the contents of the latter cannot be reached until the seal is cut or broken, and when this is done an efficient discharge-spout is at hand.

In the accompanying drawing, A is the nozzle, adapted to be soldered or otherwise secured to a liquid-package. It is made cylindrical in form and provided with a closed top, B, of thin or soft metal, which must be cut by some sharp instrument in the line of the shoulder C before the interior of the nozzle can be reached. D is the fixed section of the discharge-spout, placed within the nozzle in an inclined position, and firmly

secured to the bottom E around an opening therein, as shown in Fig. 2. F is the detachable section of the spout, which, when the nozzle is sealed, is held within the same, as shown in Fig. 1, and when the nozzle is unsealed is applied to the fixed section D to form a long discharge-spout, as shown in Fig. 2.

By this construction a sealed safety-nozzle is formed which prevents the contents of the package from being tampered with during transportation, which forms a safe receptacle for the detachable section of the discharge-spout, and which, when cut open or unsealed, is adapted to form an efficient discharge-spout, by which lamps and other small vessels can be filled with the utmost cleanliness. If desired, the detachable section of the spout may be dispensed with, as the inclination and length of the fixed section are so adjusted that even without the additional section the liquid can be discharged over the walls of the nozzle without coming in contact therewith.

Having thus described my invention, what I claim as new therein, and desire to secure by Letters Patent, is—

1. A nozzle or top for liquid-packages having within it a fixed discharge-spout, substantially as described, for the purpose specified.
2. A nozzle or top for liquid-packages provided with an interior discharge-spout composed of fixed and detachable sections, substantially as described, for the purpose specified.

HENRY H. ROGERS.
